(57) **CLAIM**

An ornamental design for a shingle gutter clip, as shown and described.

DESCRIPTION

FIG. 1 is a perspective view of a shingle gutter clip showing our new design;

FIG. 2 is a right side elevational view thereof, the left side elevational view being a mirror image;

FIG. 3 is a top plan view thereof;

FIG. 4 is a bottom plan view thereof;

FIG. 5 is a rear elevational view thereof;

FIG. 6 is a front elevational view thereof;

FIG. 7 is a perspective view thereof showing alternate environmental structure in broken lines;

FIG. 8 is a perspective view thereof showing alternate environmental structure in broken lines;

FIG. 9 is a perspective view thereof showing alternate environmental structure in broken lines;

FIG. 10 is a perspective view thereof showing alternate environmental structure in broken lines;

FIG. 11 is a right side elevational view thereof in use at a smaller scale; and,

FIG. 12 is a right side elevational view thereof in use in an alternate environment at a smaller scale.

The broken line showing of various environmental structures in all of the figures is included for the purpose of illustrating environment and forms no part of the claimed design.
